CLAIM

The ornamental design for a pair of false sideburns for sunglasses, as shown and described.

DESCRIPTION

FIG. 1 is a top perspective view of a pair of false sideburns for sunglasses showing my new design;

FIG. 2 is an exterior side view of the left false sideburn shown in FIG. 1;

FIG. 3 is an interior side view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the sunglasses in FIG. 1 is for illustrative purposes only and forms no part of the claimed design. The showing of the left false sideburn in FIGS. 2-7 is for ease of illustration only and in FIGS. 2-7 the right false sideburn is a mirror image of the left false sideburn.
